UNITED STATES PATENT OFFICE.

GEORGE JONES ATKINS, OF LONDON, ENGLAND.

ELECTROLYTIC APPARATUS FOR MANUFACTURING CERTAIN SALTS SUITABLE FOR THE SUBSEQUENT PRODUCTION OF CHLORIN.

SPECIFICATION forming part of Letters Patent No. 699,907, dated May 13, 1902.

Application filed August 17, 1901. Serial No. 72,405. (No model.)

To all whom it may concern:

Be it known that I, GEORGE JONES ATKINS, a subject of the King of Great Britain, residing at London, England, have invented a certain new and useful Electrolytic Apparatus for Manufacturing Certain Salts Suitable for the Subsequent Production of Chlorin; and I do hereby declare the following to be a full, clear, and exact description of the invention, such as will enable others skilled in the art to which it appertains to make and use the same.

It is well known that chlorid of sodium may be decomposed electrolytically. It is well known also that under different conditions the electrolysis of chlorid of sodium will produce different results, producing sometimes metallic sodium and chlorin, sometimes chlorate of sodium or hypochlorites or oxychlorids of sodium, and sometimes caustic soda and chlorin.

The object of this invention is to produce by electrolysis a mixture of chlorate of sodium and oxychlorid of sodium and chlorid of sodium in a commercial and economical manner with a view to the production from such mixture by a subsequent operation of chlorin for use in the arts.

For the purpose of my invention I employ electrolytic apparatus constructed and arranged as shown in the annexed drawings, in which—

Figure 1 is a longitudinal sectional elevation, Fig. 2 a transverse section, and Fig. 3 a plan, of the said apparatus.

35 *a* is a long trough-like containing vessel, made of wood or other suitable material, lined with carbon *b*, for example, which carbon becomes the anode. In the trough thus formed I cause to revolve a cylinder *c*, preferably of wood, but entirely incased in sheet-lead or other suitable conductor *d*. This cylinder becomes the cathode and is mounted in suitable bearings *e f* in the ends of the vessel *a*, as shown. The whole apparatus is so constructed that the space between the surface of the cylinder *c* and the surface of the carbon anode *b* in the vessel *a* may be about two inches. This trough *a b*, with its contained cylinder *c*, is so arranged that there is a natural 40 slow flow of the electrolytic solution from the one end to the other, the solution entering the

trough at *a'* and leaving it at *a''*. The cathode *d* is caused to revolve by means of the belt-pulley *g*, for example, and the electrolyte, which may consist of a solution of sodium chlorid, for example, is poured into the trough to such a level as to cover the carbon anode *b* and, preferably, somewhat less than half the diameter of the cathode *c d*, the object being that the axis of the cathode should be 55 out of the electrolytic solution.

Above and resting on the cathode *c d* along its entire length I place a scraper *h*, of india-rubber or felt or other suitable material, the object of which scraper is to remove and push 65 back the adhering electrolyte solution and liberate the bubbles of hydrogen as the cathode revolves and to clear the surface from hydrogen before it re-enters the electrolyte on the other side.

I connect the apparatus with a dynamo or other convenient source of electric current by means of the conductors *i* and *j*, for example. I find it convenient to use a current of a pressure not exceeding four volts, and if 70 the electrolytic solution is kept in order and if the surface of the cathode is kept carefully free from hydrogen polarization is avoided, and I am able to utilize a very large flow of electric energy as measured in amperes. 75

My aim in using the apparatus described is that the electrolytic decomposition should be as nearly as possible as follows: decomposition of the water with evolution and liberation of the hydrogen and combination of the 85 released oxygen and formation of the oxychlorids in the chlorid solution. Any substantial evolution of chlorin or formation of hydrochloric acid is an indication that the apparatus is not being worked in its most perfect manner.

It will be obvious that the flow of solution entering at one end at *a'* of the trough may be readily so adjusted to the effective electrolytic decomposition of the chlorid of sodium that by the time the solution arrives at the other end of the trough, so as to overflow at *a''*, the salt in solution shall consist approximately of three parts, by weight, of chlorid of sodium to one part of chlorate and oxychlorid of sodium, this being the most effective proportion for the subsequent production 90 95 100

of chlorin. The solution may either be used as it comes from the trough for the purpose of producing chlorin or the water may be evaporated and the salts thereby recovered for future use, when they can be redissolved in water and utilized as required. Chlorin may be obtained from these salts either by using sulfuric acid or any other suitable acid or acid salt in a manner that forms the subject-matter of another application for patent, Serial No. 53,136, filed March 27, 1901.

I claim—

Electrolytic apparatus for manufacturing certain salts suitable for the subsequent production of chlorin which consists of a long trough-like vessel *a* lined with a suitable anode *b*, a cylinder *c* cased in sheet-lead form-

ing a cathode arranged to rotate in the trough-like vessel *a*, connections *i, j* with a source of electricity arranged to deliver a current of not more than say four volts of electromotive force to the electrolyte, a flexible scraper *h* to remove the adhering electrolyte solution and the bubbles of hydrogen from the rotating cathode, an inlet *a'* for electrolyte solution at one end of the trough and an outlet *a''* for same at the opposite end of the trough, substantially as described.

In witness whereof I have hereunto set my hand in presence of two witnesses.

GEORGE JONES ATKINS.
